UNITED STATES PATENT OFFICE.

JOHN S. SURBAUGH, OF VINCENNES, INDIANA.

SHOVEL, SCOOP, &c.

1,312,766.

Specification of Letters Patent. Patented Aug. 12, 1919.

Application filed March 7, 1918. Serial No. 220,934.

To all whom it may concern:

Be it known that I, JOHN S. SURBAUGH, a citizen of the United States, residing at Vincennes, in the county of Knox and State 5 of Indiana, have invented certain new and useful Improvements in Shovels, Scoops, &c., of which the following is a specification.

The present invention relates to shovels, 10 scoops, spades, and kindred implements, and relates more particularly to detachable connections between the handles and blades or heads of such tools.

It is the object of the invention to provide 15 novel and improved means for detachably connecting the handle and blade in such a manner that prying, torsional leverage and other strains are successfully resisted, and at the same time, permitting the handle and 20 blade to be readily separated for replacing either, especially the blade, should the same become worn out or broken, thus providing for economy.

A further object of the invention is the 25 provision of such a connection or joint utilizing but a single securing element, thus minimizing the cost of manufacture, and also enhancing the efficiency of the implement.

30 A still further object is the provision of the improvements of the nature indicated, which provide thorough rigidity of the tool, and enable the parts to be readily and economically manufactured and assembled.

35 With the foregoing and other objects in view, which will be apparent as the nature of the invention is better understood, the invention resides in the novel construction and arrangement of parts hereinafter described and claimed, it being understood 40 that changes can be made within the scope of what is claimed without departing from the spirit of the invention.

The invention is illustrated in the accompanying drawings, wherein—

45 Figure 1 is a perspective view of a shovel or scoop incorporating the improvements, a portion of the handle member being broken away.

50 Fig. 2 is a longitudinal median section of the connection.

Fig. 3 is an enlarged cross section on the line 3—3 of Fig. 2.

Figs. 4 and 5 are views similar to Fig. 2 55 showing modifications.

Fig. 6 is a bottom view of a reinforced handle member.

Figs. 7 and 8 are plan views of different forms of tools utilizing the improvements.

The shovels or scoops shown in the drawings are of the pattern known in the trade as "hollow-back", although it is to be understood that the features of this invention can be used in various implements and tools for which they are suited, the invention resembling in some respects the shovels, scoops, etc., shown in my Patent No. 1,247,032, granted November 20, 1917, but having decided improvements thereover as herein-after described and claimed. The structure 60 shown in said patent requires several securing elements, whereas the present one necessitates but a single securing element, thus cutting down the cost of manufacture and the time required for assemblage. 75

Referring in detail to that form of the invention depicted in Figs. 1, 2 and 3, the blade or head 1 of the shovel or scoop comprises a bottom having upturned sides and back, stamped from sheet metal. The back 80 and rear end of the bottom have an up-stroke roll 2 extending forwardly from the rear edge of the blade, and this roll is forked or bifurcated as shown, so as to have the forwardly diverging ribs or prongs 3 up-struck from the bottom of the blade to effectively stiffen and reinforce the same. 85

The roll or arched portion 2 provides a recess or pocket thereunder for the reception of the handle member, as will herein-after more fully appear, and a transverse rod or cross member 4 extends underneath the crown of the roll near the rear end thereof and its terminals extend through the side walls of said roll and are securely anchored thereto. This can be done in various suitable ways, and as shown, the member 4 is in the form of a rivet having the heads 5 at its ends. It is preferable to provide washers 6 underneath the heads 5 to bear 90 against the side walls of the roll and thus distribute the strains, and avoid the member 4 tearing loose, although various equivalent means for the same purpose can be used, which need not be illustrated or described in detail. The cross member 4 forms a stirrup or seat for the clamping of the handle member between it and the crown of the roll, and said member further provides a tie and stay between the side 95 100 105 110

walls of the roll to strengthen the blade at this point. Said member 4 is preferably of concaved curvature from end to end so as to better withstand and take up the strains.

5 The handle member 7 is tubular as shown, and may be the shank proper or a sleeve or socket for the reception of a wooden shank, whichever is preferred. Said handle member 7 can be readily bent from sheet metal,

10 and for the purposes of this invention is cut away, as at 8, at its bottom portion and forward end, thus leaving an arched forwardly-projecting tongue 9 at the forward end of the handle member, which is so shaped as to

15 slip forwardly into the recess or cavity of the roll 2 over the member 4 and thus snugly fit the crown of the roll with the basal end of the tongue or portion 9 over said member 4. The tongue 9 is preferably strengthened

20 by a cross tie or stay 10 having its terminals riveted or otherwise secured to the edge portions of the tongue 9, preferably near the forward end thereof. This serves to hold the tongue in shape, and if desired, the edge

25 portions of the tongue 9 can be spread apart, as seen in Fig. 3, so as to snugly fit against the side walls of the roll 2.

The means for clamping or locking the handle member in the roll embodies a lock

30 lever 11 within the forward end portion of the handle member, and having its rear end mounted pivotally upon a transverse pivot 12 engaged through the sides of the handle member in rear of the tongue 9. This lock

35 lever 11 projects forwardly underneath the tongue 9, and is of a size to pass over the tie member 4 when the tongue 9 is introduced into the roll 2, said lever having a lower transverse groove 13 to engage and fit on the

40 member 4 when the handle member is in place. This groove 13 is between the ends of the lever, and a clamping screw 14 is threaded upwardly through the lever 11 near its free end or between said end and the

45 groove 13, so that the upper end or tip of the screw bears upwardly against the crown of the tongue 9.

After the blade and handle member are brought together, the screw 14 can be readily threaded through the lever, and when said screw is tightened it will result in the parts being securely and rigidly clamped together and locked. This is due to the fact that the lever 11 seats on the member 4 and

50 the screw 14 being forced upwardly will press the tongue 9 tightly up against the crown of the roll 2, and the groove 13 engaging the member 4 locks the handle member in the roll so that it can

55 not be accidentally withdrawn. The connection thus provided fulfills all of the requirements, and uses but a single securing element. When the screw 14 is removed, the handle member and blade can be readily

60 pulled apart or separated, for replacing

either of them when broken or worn out. The member 4 stands the prying strain of the implement, and also strengthens the blade materially or stiffens it to stand the torsional strain, as well as the pressure exerted between it and the roll for holding the handle member in place without any loose play whatever.

Fig. 4 illustrates a modification, in that the screw is replaced by a wedge 14' driven rearwardly between the lever 11 and tongue 9 to accomplish the same purpose, because said wedge forces the lever down on the member 4 and forces the tongue 9 against the crown of the roll. Such an arrangement is a desirable one, it being noted that the wedge contacts with the tongue 9 for a considerable portion of its length, whereas the screw 14 has but a single point of contact with the tongue, so that the wedge distributes the pressure better.

Fig. 5 shows a further modification, in which both the lever and screw are dispensed with, the handle member 7 having a groove or notch 13' at the basal end of the tongue or portion 9 to engage on the member 4, and a wedge 14' is driven forwardly between the crowns of the roll 2 and tongue 9 thereby clamping the handle member itself on the member 4. This is the most simple, although possibly not the most desirable form of those shown. Each of them, as will be noted, includes expansible means for the forward portion of the handle member to clamp it between the tie member 4 and roll 2, which, generally speaking, is the essence of the invention.

Fig. 6 illustrates a reinforced handle member 7. A reinforcement 15 is fitted within the forward end portion of the handle member 7 and tongue 9, and is shaped to conform thereto. This reinforcing member 15 strengthens and stiffens the handle member where the greatest strains are.

As shown in Fig. 7, the invention is used with a plain roll 2, the blade having stiffening ribs 16 at the opposite sides of said roll in lieu of the fork. Fig. 8 shows the invention used with a different style of blade having the forked roll. These figures depict only a few of the many applications of the present improvements as covered by the following claims.

Having thus described the invention, what is claimed as new is:

1. A tool embodying a blade having a roll with a seat thereunder connected rigidly with both sides of the roll, a handle member to enter freely between said roll and seat, and means operable after the handle member is moved between said roll and seat for clamping said handle member therebetween and operable for releasing the handle member for withdrawal.

2. A tool embodying a blade having a roll

- with a seat thereunder connected rigidly with both sides of the roll, a handle member insertible freely between said roll and seat, and means to bear on said seat and operable by hand after the handle member is inserted between said roll and seat for clamping the handle member against said roll, and also operable to release said handle member for withdrawal.
- 10 3. A tool blade having a roll, with a seat thereunder, a handle member to enter freely between said roll and seat, and means for engaging one of the parts of the blade and operable for clamping the handle member between the roll and seat against one of them.
- 15 4. A tool embodying a blade having a roll with a seat thereunder, a handle member between said roll and seat, and expansible means for clamping the handle member between the roll and seat.
- 20 5. A tool embodying a blade having a roll with a seat thereunder, a tubular handle member extending between said roll and seat, and means within the handle member bearing on said seat for clamping said member against the roll.
- 25 6. A tool embodying a blade having a roll with a seat thereunder, a handle member extending between the roll and seat, a member bearing on the seat, and means between said members for forcing them, one against the seat and the other against the roll.
- 30 7. A tool embodying a blade having a roll with a seat thereunder, a tubular handle member extended between said roll and seat, a member within the handle member bearing on the seat, and means between said members for forcing them, one against the seat and the other against the roll.
- 35 8. A tool embodying a blade having a roll with a seat thereunder, a handle member extending between said roll and seat, a lock member connected to the handle member and bearing on and engaging the seat to prevent longitudinal movement, and means for forcing said members, one against the seat and the other against the roll.
- 40 9. A tool embodying a blade having a roll with a seat thereunder, a tubular handle member extending between said roll and seat, a lock member within and connected to the handle member and arranged to bear on and engage the seat and prevent longitudinal movement, and means for forcing said members, one against the seat and the other against the roll.
- 45 10. A tool embodying a blade having a roll with a seat thereunder, a handle member extending between said roll and seat, a lock lever pivoted to the handle member to bear on the seat, and means between said lever and handle member for forcing them against the seat and roll, respectively.
- 50 11. A tool embodying a blade having a roll with a seat thereunder, a tubular handle member extending between said roll and seat, a lock lever pivoted within the handle member and arranged to bear on said seat, and means between said lever and member for forcing them against said seat and roll, respectively.
- 55 12. A tool embodying a blade having a roll, a cross tie member having its ends connected rigidly to the sides of the roll, a handle member insertible freely between the roll and tie member, and means operable by hand for clamping the handle member between the roll and tie member.
- 60 13. A tool embodying a blade having a roll, a cross tie member connecting the sides thereof, a handle member extending between said roll and member, and expansible means for clamping said handle member between the roll and member.
- 65 14. A tool embodying a blade having a roll, a cross tie member connecting the sides thereof and rigid therewith, a handle member extending between said tie member and roll, and means bearing on said tie member and operable for pressing the handle member against the roll.
- 70 15. A tool embodying a blade having a roll, a cross tie member connecting the sides thereof, a handle member extending between the tie member and roll, a member bearing on the tie member, and means between the third named and handle members for forcing them, one against the tie member and the other against the roll.
- 75 16. A tool embodying a blade having a roll, a cross tie member connecting the sides thereof, a tubular handle member extending between said roll and tie member, a member within the handle member bearing on the tie member, and means between the third named and handle members for forcing them, one against the tie member and the other against the roll.
- 80 17. A tool embodying a blade having a roll, a cross tie member connecting the sides thereof, a handle member extending between the tie member and roll, a lock member connected to the handle member and engaging over the tie member, and means for forcing said lock and handle members against the tie member and roll, respectively.
- 85 18. A tool embodying a blade having a roll, a cross tie member connecting the sides thereof, a tubular handle member extending between said tie member and roll, a lock member within and connected to the handle member and arranged to engage over the tie member, and means between the lock and handle members for forcing them against the tie member and roll, respectively.
- 90 19. A tool embodying a blade having a roll, a cross tie member connecting the sides thereof, a handle member extending between the tie member and roll, a lock member within and connected to the handle member and arranged to engage over the tie member, and means between the lock and handle members for forcing them against the tie member and roll, respectively.

thereof, a handle member extending between said tie member and roll, a lock lever pivoted to the handle member and engageable over the tie member, and means for forcing said lever and handle member against the tie member and roll, respectively.

20. A tool embodying a blade having a roll, a cross tie member connecting the sides thereof, a tubular handle member extending between said tie member and roll, a lock lever within and pivotally connected to the handle member and having a groove to engage over the tie member, and means between the lever and handle member for forcing them against the tie member and roll, respectively.

21. A tool embodying a blade having a roll, a cross tie member connecting the sides thereof, a handle member cut away at one end to provide a tongue to pass over the tie member under the roll, and means between said tongue and tie member for forcing the tongue up against the roll.

22. A tool embodying a blade having a roll, a cross tie member connecting the sides thereof, a handle member cut away at one end to provide a tongue to pass over said tie member under the roll, a lock member connected to the handle member and extending under the tongue to engage over the tie member, and means for forcing said lock member and tongue against the tie member and roll, respectively.

23. A tool embodying a blade having a roll, a cross tie member connecting the sides thereof, a handle member cut away at its forward end and forming a tongue to pass over the tie member under the roll, a lock lever pivoted within the handle member, extending forwardly under the tongue and having a groove to engage over the tie member, and means between said lever and tongue for forcing them against the tie member and roll, respectively.

In testimony whereof I hereunto set my hand this 5th day of March, 1918.

JOHN S. SURBAUGH
